DOOR CLOSER

Roy S. Sanford, Woodbury, and Paul F. Simpson, Washington, Conn., assignors to The Autoyre Company, Inc., Oakville, Conn., a corporation of Connecticut

Continuation of application Serial No. 696,232, September 11, 1946. This application December 13, 1950, Serial No. 200,619

9 Claims. (Cl. 16—72)

1

The present invention relates to improvements in devices for holding a door alternately in closed and open positions without necessitating the usual type of latches which have customarily been used for this purpose.

On many occasions it is necessary or desirable to hold a door in an open position and also to hold it in a closed position. It has been customary in the past to employ automatic door closers working either by springs or pneumatically in order to effect the closing of a door, usually also accompanied by certain devices for minimizing the slammimg of the door and to effect its closing in a quiet manner.

There are, however, certain types of doors, one example of which are the doors of medicine cabinets, where it is very desirable that the door, which is usually provided with a mirror, be kept in a closed position, while under other circumstances it is desirable to have the door swung fully open so as to afford access to the contents of the medicine cabinet, but without danger of having the door suddenly start to close, as for example under the influence of a draft, which might knock things from the hands of the person taking them from the cabinet.

The invention, however, is not limited to this particular type of door but, merely for purposes of exemplification, will be described in connection therewith.

It is one of the objects of the invention to provide a device which serves a double purpose, one being to maintain the door in a closed condition without the necessity for a latch, and the other being to keep the door in substantially open position, without danger of it suddenly closing.

A further object of the invention is to provide a device which will both limit the extent of opening of the door while also serving to maintain it in an open position.

Other objects of the invention will appear from the further description hereinbelow when considered in connection with the concurrently filed drawings, in which

Fig. 1 is a top plan view, partly in section, showing one modification of the device of the present invention, with the door in the open position;

Fig. 2 is a view similar to Fig. 1, showing the door in a position intermediate between open and closed;

Fig. 3 is a view similar to Figs. 1 and 2, but shown with the door entirely closed;

Fig. 4 is a partial elevational view, also partly in section, of the device illustrated in its various positions in Figs. 1, 2 and 3;

Fig. 5 shows a top plan view, partly in section, of a modification of the invention with the door in its closed position, and shown in dotted lines in partly open position; and

Figs. 6, 7 and 8 are top plan views, partly in section, of a further modification of the present invention with the door shown respectively in the closed, partly opened, and fully opened positions.

Generally speaking, the construction involved in the present invention comprises a door which is hingedly mounted for the usual swinging movement between open and closed positions, being provided also with a suitable closure link, one end of which is pivotally connected to the door at some point intermediate its vertical edges. This closure link serves both to maintain the door in open position and in some embodiments also to prevent the door from swinging beyond the predetermined open position, while at the same time the link serves as a means for keeping the door closed, dependence being had upon the resilience of the material from which the various parts are constructed.

In one embodiment the link itself may be made of a bendable but resilient or flexible material while in other embodiments, for example Figs. 5 through 8, certain resilient surfaces such as in the form of a spring or the like may be employed, while the link itself is rigid.

Referring now primarily to the construction shown in Figs. 1 through 4, the invention is there illustrated in connection with the door of a medicine cabinet 9. The cabinet 9 may, for example, have an upper frontal portion made of metal, for example consisting of two spaced walls or surfaces 10 and 11, respectively, these being spaced from each other and located in vertical planes so as to leave a space 12 therebetween. A slot 13 serves to receive the closing link 14 which is suitably pivotally connected at the point 15 to the door 16 which latter is mounted upon the hinges 17, so that it may assume either the open position shown in Fig. 1, or the closed position shown in Fig. 3, and the intermediate position shown in Fig. 2. The link 14 may be provided with a suit-

able head 18, which by engaging the wall 10 above and below the slot 13, will keep the door from opening any further than the position in which it is substantially at right angles to the surfaces 10 and 11. For that purpose, the head portion 18 of the link 14 is wider than the link, so that it cannot be pulled entirely out of the slot. In erecting this structure the link 14 may be placed in a position at right angles to that shown in Fig. 1, and then the end 18 inserted into the slot 13, and the link then turned 90° whereafter it is pivoted at the point 15 as already mentioned. This, therefore, will allow the link 14 freely to slide in the slot.

It should be particularly noted that the link 14 is made of a flexible, bendable, resilient material which is capable of considerable distortion but sufficiently resilient to again assume its original position when any restraining influence thereon has been released.

Preferably the link 14 is preformed by providing a permanent bend or knee 19 therein to insure proper sliding movement of the head end 18 along the rear surface 11. When the door is in the completely open position, as shown in Fig. 1, the stop 18 will keep the door from moving any further than the position at right angles to the surface 10. When, however, the door is moved toward the partially closed position shown in Fig. 2, the end 18 of the link 14 slides freely along the rear surface 11 until an intermediate portion of the link engages the end 20 of the slot 13 and continued movement of the door will cause bending of the link 14 in the space 12 as the end 18 continues to slide along the surface 11. The link 14 being formed of resilient material tends to return to its normal unbent condition and the force thus exerted by the link opposes further closing movement of the door. However, continued closing movement of the door from the position shown in Fig. 2 toward the position shown in Fig. 3 causes further movement of the end 18 of the link along the surface 11 and further stressing of the link until a point is reached wherein the angular relation of the link relative to the surface 11 and the point of engagement of the link with the end 20 of the slot is such that the tendency of the link to straighten out exerts a closing force on the door 16. Thus the link 14 as soon as the door reaches a predetermined position functions to close the door and hold it securely in the closed position.

In opening the door, it is only necessary to pull the door toward the open position, when a point will soon be reached, corresponding approximately to the position shown in Fig. 2, where the tendency of the link 14 to straighten itself out will push the door toward the fully open position.

Thus, as shown, the walls 10 and 11 forming space 12 which receives the link 14, and in which the latter slides during swinging movement of the door, are spaced apart a distance greater than the thickness of the link 14. With such an arrangement, the end 18 only of the link in moving from the position shown in Fig. 1 to those illustrated in Figs. 2 and 3, engages only the rear wall 11, while the side of the link intermediate its ends engages only the end 20 of slot 13. Since the above engagement is of a sliding nature on the wall 11 and at the end 20 of the slot 13, the link will be bent between the pivot 15 of the end 18 during movement of the door. As will be perceived from Fig. 2, a maximum bending of the link occurs when the parts occupy the relative

positions shown in this figure which represents an intermediate position of the door. With the spacing of the walls 10 and 11 as stated, the link is thus stressed during movement of the door to assist or oppose door movement depending on the direction of movement from an intermediate position such as that shown in Fig. 2. In further explanation, it will be understood that during movement of the link, the latter is supported for such movement at three places only, these being the pivot 15 at the outer end of the link, the engagement of the wall 11 with the free end 18 of the link, and the engagement of the front surface of the link with the edge 20 of the slot 13 formed in the wall 10 and spaced outwardly from wall 11 a distance greater than the thickness of the link, as shown in Figs. 1 to 3. Thus the slot end or abutment 20 serves to stress the entire link by bending that portion between the pivoted end 15 and the free end 18 toward the wall 11 as the door is moved to closed or open position. It will be further understood that as the door 16 is moved toward closed position from the intermediate position shown in Fig. 2, where a maximum bending of the link 14 occurs, a point will be reached where the tendency of the link 14 to straighten out, due to the stresses imparted to it by the bending thereof, will overcome the frictional force between the end 18 and the wall 11. When this occurs, the link 14 will straighten, the door 16 will be automatically closed to the position shown in Fig. 3 and will remain in closed position. On the other hand, when the door 16 is moved toward the open position from the position shown in Fig. 2, a point will be reached where the tendency of the link 14 to straighten will overcome the frictional force between the end 18 and the wall 11. When this occurs, the door will be automatically opened to its full open position.

In the modification of the device illustrated in Fig. 5, a door 21 mounted on hinges 22 is spaced in front of a housing 23 having a forward wall 24 and a rear wall 25, the forward wall being provided with a slot or opening 26. It is contemplated that this housing 23 be placed near the upper portion of the door so as not to interfere with access to anything which may be behind it, being either medicine cabinet, closet, room, or other space.

Pivoted secured to the top edge face of the door 21 at the point 27, is the relatively rigid link 28 which extends through the opening 26 into the housing 23 and is in slidable engagement with the rear wall 25 thereof. The said rear wall 25, however, is formed to provide a resilient tongue or spring 31 along which the free end 29 of the link 28 may slide. The end 29 of the link 28 is preferably bent so as to lie, in the closed position, substantially flat against the spring 31, as shown in Fig. 5.

The left end of the slot 26 is defined by the abutment 33 which may, if desired, be suitably rounded so that the link 28 may freely slide thereon. With the door in the closed position the link 28 will extend from its point of pivotal connection 27 to a point intermediate the ends of spring 31. Thus force will be transmitted through the link 28, which now acts as a first class lever with its fulcrum 33, to hold the door in the closed position. When the door, however, is opened and gets into the position which is shown in dotted lines in Fig. 5, the first effect will be to bend the spring 31 outwardly toward the rear until a point is reached, about as shown

in the drawings, where the spring 31 will exert a pushing action against the link 28 serving to push it out of the housing imparting an outward swinging movement to the door 21. The door will then be held in that position until it is deliberately closed whereupon the link 28 will again move the spring 31 rearwardly until eventually the spring will push the end 29 into the position shown in full lines in Fig. 5, thereby again holding the door closed.

A further embodiment of the invention is shown in Figs. 6, 7 and 8 and constitutes a construction suitable for heavier doors. In the construction shown in these figures a suitable door 34 is hinged to a door frame 35 by means of the hinges 36. At the opposite side of the door, and only along the upper portion thereof, the door abuts against a stop member 37 which extends to a point about one-third to one-half way across the width of the door 34.

The holding and operating means of the door in this type of construction comprises a pivot-supporting member 38 to which is attached a rod 39 by means of the pivot 40, which rod 39 is in sliding engagement with the edge 41 of the stop member 37 which forms a fulcrum for the rod 39. The rod extends behind the stop member 37 and is urged thereagainst by means of a spring 42 which preferably takes the form shown in the figure, consisting of a substantially straight portion and a curved portion 43 which again assumes a substantially straight continuation 44. The free end of the rod 39 is suitably rounded so that it may freely slide along the spring 42. This spring is suitably supported in a block 45, but its free end is capable of being moved rearwardly relative to the door by the free end of the rod 39.

When the door is in the position shown in Fig. 6, the end 44 of the spring urges the free end of the rod 39 against the stop member 37, so that the rod 39, acting against the fulcrum 41, will force the door inwardly to a closed position without the necessity of any other holding means. If, now, the door is partly opened as shown in Fig. 7, the end of the rod will push the spring backwardly while at the same time the rod will slide along the fulcrum 41. When the door is still further opened the free end of the rod moves past the shoulder between the flat end 44 and the curved portion 43 whereupon the force exerted by the spring on the rod 39 includes a substantial component tending to open the door whereby the door is forced by the spring 42 to the open position shown in Fig. 8.

Fundamentally the principles involved in the various embodiments are the same, namely that either a link 14 or 28, or rod 39 is used alternately to keep the door open and closed. In the construction shown in Figs. 1, 2, 3 and 4, the link itself is resilient or flexible, that is to say, of a springy nature, while in the construction shown in Figs. 5 through 8 a separate spring is relied upon to exert the desired force. In all constructions the link or rod operates in a suitable housing which is preferably near the top of the door so that free access can be had to anything normally concealed by the door. The material which may be used for the purpose of constructing the link 14 may be a suitably tempered metal or spring steel while in the construction shown in Figs. 5 through 8 the rod may be made of any suitable material, either metallic, wood, plastic, or the like.

While we have shown particular embodiments of our invention, it will be understood, of course,

that we do not wish to be limited thereto since many modifications may be made, and we, therefore, contemplate by the appended claims to cover any such modifications as fall within the true spirit and scope of our invention.

This application is a continuation of our application, Serial Number 696,232 filed September 11, 1946, now abandoned.

Having thus described our invention, what we claim and desire to secure by Letters Patent is:

1. In a door construction having a frame and a door hingedly mounted thereon, a device for holding the door in open or closed position and operable upon movement of the door from an intermediate position toward open or closed position to urge the door toward a corresponding position, comprising an elongated link member having one end thereof pivotally connected to the door, the other end of the link being free, means providing an elongated surface member along which the free end only of the link member slides as the door is moved to an open or closed position, a stationary abutment carried by the frame and positioned adjacent the door when the latter is closed, said abutment being spaced from said surface member a distance greater than the thickness of said link member and being positioned to slidably engage the link member intermediate the ends thereof as the door is moved to open or closed position, the link member extending through the space between the abutment and the surface member and having its free end only slidably engaging the surface member and with the link arranged at an acute angle with respect to said surface member at all times during opening and closing of the door, at least one of said members being resilient to stress the link during movement of the door toward open or closed position.

2. In a door construction having a frame and a door hingedly mounted thereon, a device for holding the door in open or closed position and operable upon movement of the door from an intermediate position toward open or closed position to urge the door toward a corresponding position, comprising an elongated spring link having one end thereof pivotally connected to the door, the other end of the link being free, a member carried by the frame and providing a surface along which the free end only of the link slides as the door is moved to an open or a closed position, and means for bending the entire link between its pivoted end and its free end to stress the link during movement of the door, comprising a stationary abutment carried by the frame and spaced from said surface a distance greater than the thickness of said link, said abutment being positioned to slidably engage the link intermediate the ends thereof as the door is moved to open or closed position, and to effect a maximum bending of the link when the door is in an intermediate position, the tendency of the link to assume a straightened position due to the stress imparted thereto by the bending thereof effecting an automatic closing or opening of the door when the latter is moved toward closing or opening position from said intermediate position.

3. In a door construction having a frame and a door hingedly mounted thereon, a device for holding the door in open or closed position and operable upon movement of the door from an intermediate position toward open or closed position to urge the door toward a corresponding position, comprising an elongated spring link

having one end thereof pivotally connected to the door, the other end of the link being free, means carried by said frame to provide a pair of spaced apart front and rear walls positioned substantially parallel to each other and substantially parallel with the door when the latter is closed, the front wall having an elongated slot formed therein, said slot provided with opposite edges, and the distance between said walls and the length of said slot being greater than the thickness of said link, the free end of the link passing through the slot to engage only the rear wall as the door is opened and closed, the edge of the slot more remote from the hinged mounting constituting a stationary abutment slidably engaging the link during movement of the door, said abutment being positioned to bend the link between said one end and said other end toward said rear wall a maximum amount when the door is moved to said intermediate position to stress the link, the tendency of the link to straighten out due to the stress imparted thereto due to bending thereof, overcoming the frictional force between the free end of the link and said rear wall to automatically impart a closing or an opening force to the door as the latter is moved toward a closed or opened position from said intermediate position.

4. In a door construction having a frame and a door hingedly mounted thereon, a device for holding the door in open or closed position and operable upon movement of the door from an intermediate position toward open or closed position to urge the door toward a corresponding position, comprising an elongated spring link having one end thereof pivotally connected to the door, the other end of the link being free, means carried by said frame to provide a pair of spaced apart front and rear walls positioned substantially parallel to each other and substantially parallel with the door when the latter is closed, the front wall having an elongated slot formed therein, said slot provided with opposite edges, and the distance between said walls and the length of said slot being greater than the thickness of said link, the free end of the link passing through the slot to engage only the rear wall as the door is opened and closed, the edge of the slot more remote from the hinged mounting constituting a stationary abutment slidably engaging the link during movement of the door, said abutment being positioned to bend the link between said one end and said other end toward said rear wall a maximum amount when the door is moved to said intermediate position to stress the link, the tendency of the link to straighten out due to the stress imparted thereto due to bending thereof, overcoming the frictional force between the free end of the link and said rear wall to automatically impart a closing or an opening force to the door as the latter is moved toward a closed or opened position from said intermediate position, said link being provided with a stop member on its free end within the space between said front and rear walls to engage the rear surface of said front wall to prevent opening of the door beyond a predetermined maximum amount and to allow sliding movement of the link in said slot to a position where the link engages the edge of the slot which is closer to the hinged mounting.

5. In a door structure having a door frame and a door having a hinge connection therewith, means for holding said door in closed position and for resiliently opposing opening movement thereof comprising a wall on the door frame substan-

tially parallel with the door in closed position, an abutment on said frame spaced outwardly from said wall, and a spring link extending between said door and wall having a pivoted connection at one end with the door and being slidably at the other end only on the rear side thereof along the wall, and having the entire link between said ends spaced outwardly from said wall and angularly disposed with respect thereto, with the front side of the link intermediate the ends in sliding engagement with said abutment, said abutment being positioned to bend said link between the ends toward said wall with the door in closed position and during movement toward open position.

6. In a door structure having a door frame and a door having a hinge connection therewith, means for holding said door in closed position and for resiliently opposing opening movement of said door, comprising a link having a pivoted connection at one end with said door, and means for stressing the entire link between the ends thereof to exert a closing force on the door at said pivoted connection comprising an abutment on said frame slidably engaging the link intermediate the ends thereof on the side adjacent said door, and a wall on said frame spaced rearwardly from said abutment a distance greater than the thickness of said link, with the other end only of said link being slidable along said wall as the door is opened and closed and the wall being angularly disposed to the link at said other end.

7. A door construction of the character set forth in claim 1 wherein the surface member is resilient to stress the link during movement of the door toward open or closed position.

8. A door construction of the character set forth in claim 7 wherein the elongated surface member is constituted by a rear wall carried by the frame, and the abutment is constituted by one edge of a slot which is formed in a front wall carried by the frame, said front and rear walls being parallel and being spaced apart a distance greater than the thickness of the link member.

9. In a door construction having a frame and a door hingedly mounted thereon, a device for holding the door in open or closed position and operable upon movement of the door from an intermediate position toward open or closed position to urge the door toward a corresponding position, comprising an elongated spring link having one end thereof pivotally connected to the door, the other end of the link being free, a pair of spaced apart front and rear walls carried by said frame and positioned substantially parallel with the door when the latter is in closed position, said front wall having an elongated slot therein provided with opposite edges, the free end of said link passing through the slot and slidably engaging said rear wall and with the link arranged at an acute angle with respect to said rear wall, and the distance between the front and rear walls and the length of said slot being greater than the thickness of said link, the edge of said slot more remote from the hinged mounting constituting an abutment for bending the link between its pivoted end and its free end to stress the link during movement of the door, said abutment being positioned to slidably engage the link intermediate the ends thereof as the door is moved to open or closed position, to bend the entire portion of the link extending between the ends

thereof toward said rear wall when the door is in an intermediate position and during movement in either direction therefrom, and a stop formed on the free end of said link and engageable with the rear surface of said front wall for limiting the opening movement of the door. 5
